UNITED STATES PATENT OFFICE.

ALBERT EDWARD HARVEY, OF STREETLEY, ENGLAND, ASSIGNOR OF ONE-HALF TO
GEORGE EDWARD FOLKES, OF BIRMINGHAM, ENGLAND.

APPLIANCE FOR PLAYING AN IMPROVED CARD GAME.

Application filed December 31, 1919. Serial No. 348,714.

To all whom it may concern:

Be it known that I, ALBERT EDWARD HARVEY, a subject of the King of Great Britain, residing at "Ranworth," Middleton Road, 5 Streetley, in the county of Stafford, England, have invented a new and useful Improvement in Appliances for Playing an Improved Card Game; and I do hereby declare the following to be a full, clear, and 10 exact description of the same.

This invention has reference to appliances for playing an improved card game.

The game is based on the operations of the stock exchange or the stock and share 15 market and is primarily designed as a game of chance for two or more players wherein the market fluctuations of stocks or shares are determined by means of quotation cards. The actual pack of cards for 20 playing the said game may be varied both in number and designation according to different requirements but the basis of the game and the pack remain the same.

It is desirable to distinguish the present 25 card game from the card game familiarly known in this country as "Pit," wherein the pack of cards comprises a plurality of suits, all the cards containing distinctive designations, all the cards of a suit being alike and 30 all the suits being different.

The present invention consists of a pack of playing cards for playing an improved card game, said pack comprising a plurality of stock or share cards, and a plurality of 35 quotation cards, the latter bearing a determined relation in value to the stock or share cards.

As a means of describing the present invention I propose to describe one pack of 40 cards which may be employed for playing the game, and also to briefly indicate the method of playing the game, but I wish it to be understood that considerable modifications may be made without departing from the 45 scope of the present invention.

The accompanying drawings illustrate the two types of playing card which comprise the complete game set or playing pack.

Fig. 1 illustrates two of the stock or share 50 cards, and

Fig. 2 illustrates three of the quotation cards.

Preferably the quotation cards which increase the par value of the stock or share 55 cards are printed in one colour, say red,

while the quotation cards which decrease the par value of the stock or share cards are printed in say black, moreover suitable pictorial illustrations may be embodied in the design of the stock or share cards. 60

A pack of cards according to the present invention comprises say six sets or blocks of stock and share cards one set or block being designated Shipping and marked with par value of \$10, the second set being designated 65 Motors and marked with a par value of \$10, the third set being designated Gold and marked with a par value of \$8, the fourth set being designated Oil and marked with a par value of \$8, the fifth set being 70 designated Copper and marked with a par value of \$6 and the sixth set being designated Rails and marked with a par value of \$6. The quotation cards which comprise the remainder of the pack each have markings 75 thereon such as:—par, Up 1, Up 2, Up 3, Up 4, Up 5 and Up 6, Up 50%, Up double, Par plus 1 bonus share, Down 1, Down 2, Down 3, Down 4, and Down 5, Down 50%, No change, and Smash, the number of each 80 kind of quotation cards can be varied to suit different requirements.

The preferred method of playing the game is as follows:—One of the players first acts as broker and has possession of 85 the pack of cards. He then lays out on the table the six sets or blocks of stock or share cards which as stated are each marked with a par value. Each player in turn is now given an opportunity of a purchasing choice 90 of one or more of the said shares to be paid for by means of counters representative of money values at a price which is subsequently determined by the relation that the quotation card now dealt by the broker bears 95 to the particular set or block of shares which the player has chosen. In other words the first buying of shares is a speculative buying based on an initially unknown value the 100 said value being determined after choice by the value put upon the share chosen by the quotation card which is dealt relative to the par value of the stock or share card. For example, assuming a player's (buyer's) 105 initial choice to have been gold shares having a par value of \$8 and the quotation card dealt relative thereto by the broker to be marked "Up 1" this player will have to pay to the broker \$9 in respect to each gold share bought. The second buying does not 110

take place until after a further deal of quotation cards relative to each set or block of shares has been made by the broker, this gives the buyer an opportunity of correcting 5 his initial speculative purchase or of buying other shares on a low market, for example, assuming the quotation card is now dealt relatively to motors to be marked "Down 5" the buyer could purchase motor 10 shares having a par value of \$10 at \$5 each. The buying of shares has now been completed, and the stock or share cards bought are now held by or credited to each buyer. A further deal of quotation cards relatively 15 to the sets or blocks of stock or share cards now takes place, and after this deal the broker pays the buyer for the shares he has bought, for example, assuming that on the third deal the quotation card "Up 3" is 20 dealt relatively to the gold shares and the card "Down 2" is dealt relatively to the motor shares, the broker would have to pay the buyer \$11 (\$8 \$3) per share in respect of all gold shares he has bought, and 25 \$8 (\$10-\$2) per share in respect of all the motor shares he has bought.

In order to even up the chances of the game a number of quotation cards marked "Smash" are introduced which when they

occur in the deal cause the buyer to lose all 30 his purchase of that particular share. Conversely, if the quotation card designated "Par plus 1 bonus share" should be dealt the buyer can purchase or obtain double 35 value for each of his shares. The game is primarily intended for two or more players, and is played with counters as representative of money values.

Preferably for aiding the understanding and reading of the quotation cards, the designations on the cards indicative of a rise 40 are coloured, say red; and the designations of the cards indicative of a fall are coloured say blue. Further the quotation cards are printed so as to read from both the top and 45 the bottom of the card to facilitate observation by both the broker and the buyers.

What I claim is:—

A game set comprising two packs of 50 cards, one pack consisting of a plurality of stock cards having designated thereon the par value of the stock, the other pack consisting of a plurality of quotation cards, said quotation cards determining the market value in play of the stock cards. 55

In testimony whereof, I have signed my name to this specification.

ALBERT EDWARD HARVEY.
